UNITED STATES PATENT OFFICE.

OSCAR SODERSTROM AND FRED HARRIS LYNDS, OF NORTH ATTLEBORO, MASSACHUSETTS, ASSIGNORS TO WHITING & DAVIS COMPANY, A CORPORATION OF MASSACHUSETTS.

LINK-MESH MACHINE.

Application filed June 6, 1921. Serial No. 475,214.

To all whom it may concern:

Be it known that we, OSCAR SODERSTROM, a citizen of the United States, resident of North Attleboro, county of Bristol, Massachusetts, and whose post-office address is 5 c/o Whiting & Davis Company, Plainville, Norfolk County, State of Massachusetts, and FRED HARRIS LYNDS, a citizen of the United States, and resident of North Attleboro, county of Bristol, Massachusetts, whose post-office address is c/o Whiting & Davis Company, Plainville, Norfolk County, State of Massachusetts, have invented certain new and useful Improvements in Link-15 Mesh Machines; and we do hereby declare the following to be a full, clear, and exact description of the invention, such as will enable others skilled in the art to which it appertains to make and use the same.

20 This invention relates to a machine for cutting pieces of a selected shape from a sheet of link mesh fabric.

It has been the practice, heretofore, to 25 cut designs or shapes, as for instance, those used for making mesh bags, from a piece of link mesh fabric by hand. When the cutting operation is performed in this way, the operator cuts the links one by one with scissors or a similar tool, counting the links 30 along the outline of the design as the cutting operation proceeds so that the finished shape will be of the desired design. This hand operation is tedious and necessarily slow, and constitutes a large item of cost 35 in the production of link mesh bags.

The machine of the present invention eliminates the expensive and frequently inaccurate manual operations above referred to, and is so arranged that pieces of mesh 40 of any desired shape may be outlined in the fabric with each piece an exact duplicate of every other made according to the same pattern. The machine operates rapidly and under complete control, and the change from 45 one pattern to another may be effected readily and without extended delay.

The machine is so constructed that it may 50 operate simply to outline a design on the fabric, as for example, the shape of a piece such as would be used for a handbag, by indicating or identifying the links to be removed from the fabric along the edge of the piece. For this purpose the machine may include devices for marking the selected 55 links in any suitable way so that the oper-

ator may thereafter cut or otherwise remove the marked links to produce the piece. Preferably, these devices are formed to sever the selected links so that the parts of the link will at once drop out of the fabric, 60 or else facilitate their removal by spreading apart the abutting ends of the selected links by an amount at least equal to the diameter of the link wire. When such spreading devices are employed, the entire length of fabric is passed through the machine, and, after 65 its removal therefrom, is shaken so that the spread links will drop out, thus completing the formation of the pieces of the desired shape. 70

The invention, accordingly, involves the provision of a support for the piece of fabric to be treated, and a multiplicity of link marking, spreading, or severing elements, corresponding in number and position to 75 the links in a row across the fabric. The support and the elements are so arranged that the fabric and the elements may be given a relative movement, such that successive portions of the fabric may be acted 80 on by the elements, and a second relative movement in the course of which the elements perform their function. Preferably the fabric is advanced with a step by step movement past the elements and the latter 85 are moved relative to the fabric in the periods of rest of this movement. The operation of the elements acting on the links is under the control of a pattern mechanism which may conveniently include an 90 endless roll or sheet having perforations or projections disposed over its surface according to the shape of the pieces of mesh which are to be made. The pattern mechanism is arranged to move the roll with a 95 step by step movement in correspondence with the movement of the fabric and the perforations are placed in rows to correspond with the rows of links in the fabric. Also the perforations in each row correspond 100 in position to the position of the links in a row although the number of perforations will actually be less in number than the number of links in the row unless the pattern requires that the fabric be severed entirely across. The mechanism by 105 which the pattern roll or sheet controls the action of the devices which act on the individual links includes a multiplicity of members which correspond in number to 110

- the number of elements, and in turn to the number of links in a row. In each period of rest in the movement of the pattern sheet, the members and pattern sheet are brought 5 into contact and the members take positions which are determined by the location of the perforations in the pattern sheet. When such action has taken place, selected members will have been disposed so as to bring 10 into action the elements by which the links are to be acted upon and the location of the perforations on the pattern roll thus determines which links will be marked, severed, or spread, as the case may be. 15 After the latter operation has occurred, the parts are restored to normal position and the pattern roll and the piece of fabric make another forward step, whereupon the cycle of operations is repeated. 20 The form of machine at present preferred is illustrated in the accompanying drawings, in which—
Figure 1 is a view of the machine partly in elevation and partly in section;
25 Figure 2 is a plan view of the machine partly in section;
Figure 3 is a view along the line 3—3 of Figure 1;
Figures 4, 5, 6 and 7 are detail views of 30 the link marking and separating mechanisms showing the cycle of operation;
Figure 8 is a detail plan view of the link marking and separating mechanisms and associated parts;
35 Figure 9 illustrates a pattern for an article of link mesh, and
Figure 10 represents an outline of the article marked on the link mesh fabric by the link marking and separating mechanisms.
40 Referring to Figures 4-7, the link mesh fabric 11, out of which the article of link mesh is to be cut, is suspended from a suitable supporting and feed roller 12, the face of which is preferably provided with means 45 (not shown) for engaging the links of the fabric and positively moving them forward. Slidably mounted in grooves at the top of the block 13 is a series of selector bars 14, there being one of these bars for each link 50 across the width of the fabric. The end of each of the selector bars is reduced to form a link marker or spreader 15 which is adapted to enter the link of the fabric in alignment with the bar, as illustrated in Figures 55 6 and 7. The dimensions of the link marker are such that when the marker is inserted in a link it will spread it open, parting the abutting ends of the ring of wire constituting the link an amount at least equal to the 60 diameter of the wire. The spread link is then removable from adjacent links simply by shaking the fabric. This spreading of the links is readily accomplished by the insertion of the marker, since the abutting ends of the rings of the fabric are left un-

soldered until after the article is cut to shape. The lower edge of each of the separator bars is channelled at 16 to receive the upper end of a stationary bar 17, and the bars are held in position by a cover plate 70 18 extending from one side of the machine to the other. Fastened to the block 13 is a second block 19 having a recess 20 into which the ends of the selector bars 14 may move. Keyed to a stationary shaft 21 is a 75 roll 22 having an arcuate groove 23 running the length of the roll. Passing over this roll, and actuated by means hereinafter to be described, is an endless perforated pattern roll or sheet 24, the perforations 25 in 80 which, as shown in Figure 9, outline the article to be cut from the fabric. Between the roll 22 and the block 19 is a shaft 26 on which are loosely mounted a series of feed dogs 27 corresponding in number to the 85 number of selector bars, and positioned one directly in back of each of the corresponding selector bars. The shaft 26 has a plurality of circumferential grooves 28 in which are mounted a plurality of separator bars 29 90 for separating pairs of adjacent feed dogs to insure independent motion of the latter around the shaft 25. The feed dogs 27 are each formed with an upper arm terminating in a projection 30 adapted to enter the recess 22 to block the backward movement of the corresponding selector bar into the recess; and a lower arm carrying the pin 31 adapted to enter the arcuate groove 23 in the roll 22 through the perforations 25 in 95 the pattern sheet. The center of gravity of the feed dogs 27 is disposed to the left of the shaft 26 (referring to Figures 4-7) so that the dogs tend to drop around the shaft in a counter clockwise direction resting normally 100 on the stop 32 provided by the end of the block 19. The end of the block 19 has an arcuate groove 33 in which a semi-circular rocker shaft 34 is supported. This shaft 34 is connected to actuating means to impart thereto an intermittent turning movement 110 to rotate the dogs about the shaft 26 and raise the projections 30 out of the recesses 20 to clear the ends of the selector bars 14 so that these are free to slide into the recesses. 115
The machine has a table 35, supported on legs 36. Mounted to slide between the guideways 37 on the table is a carriage 38. Supported on the carriage are the blocks 13 and 19 carrying the selector bars 14, 120 the rocker shaft 34 and the shaft 26 which is fastened in brackets 19^a secured to block 19. Also mounted on the carriage are brackets 39 for holding the shaft 21, and brackets 40 serving as bearings for a 125 pair of guide rollers 41 over which the pattern sheet 24 passes, the latter being held taut on the rollers 41 and roll 22 by a tension roller 42, loosely slung within the end of the sheet and bearing down upon 130

it. A guide 43 is adjustably secured on the shaft 26 by means of set screws 44 and extends across and contiguous to the roll 22 to prevent the pattern sheet 24 leaving the 5 roll.

The ends of the shaft 21 are squared to fit the slots 45 in the brackets 39 in which the shaft is secured by set screws 46; similarly the brackets 40 are slotted at 46^a. Thus the 10 roll 22 and the upper roller 41 may be removed, the pattern sheet taken out of the machine and a new one inserted.

Loosely mounted on the ends of the shaft 21 is a pair of feed rollers 47 for feeding 15 the pattern sheet 24 over the stationary roll 22. Each of these feed rollers has circumferentially spaced pins 49 for engaging corresponding marginal perforations 50 in the pattern sheet by which the latter is moved 20 over the surface of the roll 22. The feed rollers 47 are actuated by means of pawl and ratchet mechanisms, ratchet teeth 51 on the periphery of the rollers being engaged by spring pressed pawls 52. Each of these 25 pawls is mounted in a bayonet slot 53 in order that it may be locked in inoperative position, and the slot 53 is cut in one arm 54 of a bell crank 55 which is pivoted at 56 to the block 13. The other arms of the bell 30 cranks terminate in circular portions 57 which are held against movement relative to the table by pairs of abutments 58 secured to the table top. When the carriage 38 is reciprocated by actuating means about 35 to be described, the pivot points 56 of the bell cranks 55 are carried along with the block, and since the ends 57 of the bell cranks are held against movement with the carriage, the bell cranks oscillate about their 40 pivot points, moving the pawls 52 upwardly and downwardly, and giving to the rollers 47 a step by step movement through engagement with the ratchet teeth 51.

The table 35 has a bearing 59 in which is 45 mounted a shaft 60 having at its upper end a head 61, the latter carrying on its upper surface an eccentric pin 62. The pin 62 fits into the block 63 movable in a laterally extending recess 64 in the under side of the carriage 35. The shaft 60 carries a bevel gear 65 meshing with a bevel gear 66 on the end of a shaft 67, the latter of which is 50 mounted in a bearing 68 depending from the table 35. At the outer end of shaft 67 is a belt pulley 69 for connection to power, and also a hand wheel 70 for operating the moving parts of the machine by hand. The shaft 67 is disengageable from the driving 55 means by a clutch 71 that is engaged by arms 72, fixed on a shaft 73 at the end of which is a handle 74 for operating the clutch. When the clutch 71 is thrown in, connecting 60 the shaft 67 to power, the shaft 60 is rotated through gears 65 and 66, and the block 63, under the action of the eccentric 65

pin 62, moves the carriage 38, imparting to it reciprocatory motion toward and away from the link mesh fabric 11.

The link mesh fabric is given a step by step movement relative to the selector bars 70 14, each step corresponding to one row of links across the fabric so that at each period of rest in the movement a new row of links is presented to the selector bars to be acted upon thereby. This step by step feeding of 75 the mesh fabric is effected by imparting to the roller 12 an intermittent step by step rotation in timed relation with the step by step movement of the rollers 47 carrying the pattern sheet 24. This timed movement 80 of the roller 12 is accomplished by a rocker arm 75 loosely mounted on shaft 48, the rocker arm being actuated during the forward and backward movement of the carriage 38 by a pin 76, secured to the block 13, 85 against which the rocker arm is held by a spring 79, fixed at one end to a block 80, and attached at its other end to a pin 81 on the arm. Formed on the outer end of the rocker arm is a projection 77, and inwardly 90 along the arm from this projection is a cut away portion 78. When the carriage 38 is at its extreme outward position, that is to the right in Figure 1, the projection 77 of the rocker arm is in engagement with the 95 pin 76 and the arm is depressed by the projection in a clockwise direction to its lowermost position. When, however, the carriage moves forwardly, or inwardly toward the mesh fabric 11, the cutaway portion of the 100 arm comes in contact with the pin 76 thus producing an upward movement of the arm in a counter clockwise direction under the action of the spring 79. This movement of the rocker arm is communicated to shaft 48 105 by means of a spring pressed pawl 86 acting on the peripheral teeth 87 of the ratchet wheel 88 fixed to shaft 48. Hence, as the carriage 38 is reciprocated the rocker arm is oscillated upwardly and downwardly, producing corresponding oscillations of the 110 shaft 48 and roller 12, thus feeding the mesh fabric 11 forwardly step by step between a pair of pressure rollers 82 which preclude slipping of the fabric and insure positive, accurate feeding. The pressure rollers are mounted in split bearings, the upper parts of which are formed in a cover plate 84 hinged at 83 so that the cover plate may be opened to permit the removal of the 115 rollers 82. The cover plate is secured in closed position by the screw 85.

Referring again particularly to Figures 4-7, the beginning of the cycle of operation is indicated in Figure 4, in which position 120 of the parts the carriage is at its extreme outward position from the mesh fabric 11. The selector bars are all in alignment at the beginning of the cycle, as shown in Figure 4, and the feed dogs 27 are raised by rocker 125

shaft 34 to clear the ends of the selector bars. As the carriage moves forwardly, the rocker shaft is turned to the position indicated in Figure 5, thus permitting the dogs 5 27 to fall until the pins 32 thereof contact with the surface of the pattern sheet, or enter the perforations 25, as in Figures 5 and 6. In the latter case, the dogs fall to the stop 32, their projections 30 entering the 10 recesses 20 directly in back of selector bars 14 to prevent backward movement thereof. The feed dogs which fall without encountering perforations in the pattern sheet contact with the surface of the sheet and are 15 held in raised position clear of the ends of the corresponding selector bars. When the bars are advanced to the positions shown in Figures 6 and 7, the spreaders 15 on the ends of the selector bars, fixed in operative positions by the feed dogs, enter links A and are forced therethrough, spreading the links open by parting the abutting ends of the rings of wire constituting the links an amount equal at least to the diameter of the wire. 20 25 The tip ends of the spreaders enter the slots 89 in a block 90 secured to the block 80, the slots acting to steady the selector bars. The links A are links on the outline of the pattern of the article to be cut from the mesh, 30 and since these links are spread open, they may readily be removed to detach the article from the fabric by shaking the fabric after the operation of outlining the design is completed. The spreaders 15 of the selector bars that are not selected, or fixed in 35 operative positions to enter the links, by the feed dogs, come in contact with the mesh fabric which pushes the bars backwardly into the respective recesses 20 as the block 40 45 13 advances. These bars are brought back in alignment by the stationary bar 17 at the end of the return movement of the carriage, at which time the feed dogs are again raised by the rocker shaft 34 to clear the ends of the selector bars, thus completing the cycle.

The intermittent movement of the rocker shaft 34 is produced by an arm 91 reciprocated vertically by an eccentric 92 acting 50 through the plunger 93, the latter having a roller 94 bearing on the periphery of the eccentric. The roller 94 at the end of the plunger 93 is held against the face of the eccentric by means of a spring 93', one end 55 of which is secured to the table 35, the other to a pin extending from the arm 91. On the end of the shaft 34 is a lever 96 carrying pins 95. When in raised position the end 60 of the arm wipes the lowermost of pins 95 moving it upward thus rocking the lever and shaft. This action takes place at the beginning and end of each cycle to raise the feed dogs and permit free movement of the selector bars as explained.

65 Summarizing the operation, the recipro-

cating movement of the carriage 38 in turn causes the step by step advance of the fabric a row at a time, advances the pattern roll in correspondence with the fabric movement, brings into action, under the control of the pattern, certain of the feed dogs, and causes the selector bars which are in turn controlled by the feed dogs, to perform their function in spreading the links of the mesh. As each new row of links in the fabric is advanced to position to be operated on, a corresponding portion of the pattern is also brought into operative position. Thereupon the feed dogs are released and such of them as are in registry with perforations on the pattern are allowed to descend to a position where they serve as stops for the corresponding selector bars. When the group of selector bars is carried forward with the carriage, such of the bars as are prevented from return movement by the dogs act on the links and cause them to be spread apart, while the others move freely backward upon engagement with the links and therefore perform no spreading function. After the spreading operation has taken place, the feed dogs are raised to position out of contact with the pattern sheet, and the carriage moves back. During this latter movement the selector bars are moved away from the fabric and placed in alignment by means of the stationary bar extending through the carriage. As the carriage again moves forward, the fabric and pattern sheet are advanced one step and the operation of the selector bars and feed dogs again takes place, the several parts being actuated in proper timed relation. This cycle of operations occurs for each row of links across the fabric and continues until the piece of mesh which is to be removed from the fabric has been completely outlined, whereupon the pattern makes a second passage through the machine and a second piece of the same shape is marked out.

Fig. 10 shows a piece of link mesh fabric and a design is indicated thereon for a shape such as might be used in making a mesh bag. A piece of this shape is cut from the sheet and folded over upon itself; then the coacting edges are joined together by inserting suitable links. To get a series of pieces of this shape from the sheet, a pattern sheet is inserted in the machine having openings therein spaced to correspond with the spacing of the rings to be removed from the sheet of mesh to form the piece shown in Fig. 10. The machine is then started in operation and in each cycle of operations the sheet of mesh is moved forward one step and also the pattern sheet is moved forward one step. In each operation certain of the selector bars 14 are selected by the movement of the corresponding dogs whose projections 130

31 enter openings in the pattern sheet, and when all of the selector bars move forward, the ones that have been selected enter rings of the fabric and spread those rings slightly. 5 Thus, for spreading the rings in the line across the upper part of the design indicated in Fig. 10, a plurality of selector bars would be selected and used for spreading wings. In the next operation only two selector bars 10 would be selected and those two would operate to spread rings. The operation would be continued thus until the whole design was cut and then the endless pattern sheet would be brought around to the position 15 for repeating the operation. The operation might be repeated a great number of times, the sheet of link mesh fabric being collected in a box below the supporting roller 12.

It will be understood that in accordance 20 with this preferred operation of spreading the rings, the rings which have been spread remain in position. After a succession of the shapes have been cut out to this extent and a long piece of the fabric has collected 25 in the receiving tray, the operator takes this piece in his hands and shakes it and in the course of this shaking operation the rings which have been spread drop out rapidly and finally the shapes are no longer held in 30 position in the sheet of mesh and fall out.

It should be understood that the principles 35 of this invention may be utilized in machines employed for completely severing the rings which are to be taken out or machines in which the rings to be extracted are marked in any suitable way so that they may be identified as links which are to be cut in a subsequent operation. But the operation of spreading the rings is preferred, particularly when operating upon fine mesh fabric having rings made of very light wire as there is less danger of injury to rings of the fabric other than those which are removed. 40

We claim:

45 1. The combination of a support for a piece of link mesh fabric having the links thereof arranged in rows lengthwise and crosswise of the piece, means for moving the piece of fabric in the direction of its length, a multiplicity of elements each corresponding to a link in a crosswise row of links of the piece of mesh and adapted to act upon individual links to facilitate their removal from the piece of mesh, a pattern sheet, means for moving the pattern sheet in correspondence with the movement of the piece of mesh, a plurality of members each corresponding to one of said elements and cooperating with the pattern sheet, means 50 for moving the pattern sheet and said members relatively whereby certain of said members are selected and caused to move in a manner different from the other members, and means for actuating the elements corresponding to the members so selected to 55

cause these particular elements to act upon links of the piece of mesh in the row to which they correspond.

2. The combination of a support for a piece of link mesh fabric having the links thereof arranged in rows lengthwise and crosswise of the piece, means for moving the piece of fabric in the direction of its length with a step by step movement, one row at a step, a multiplicity of elements 70 each corresponding to a link in a crosswise row of links of the piece of mesh and adapted to act upon individual links to facilitate their removal from the piece of mesh, a pattern sheet, means for moving the pattern sheet with a step by step movement in correspondence with the movement of the piece of mesh, a plurality of members each corresponding to one of said elements 75 and cooperating with the pattern sheet, means for moving the pattern sheet and said members relatively during the periods of rest of the step by step movement of the pattern sheet whereby certain of said members are selected and caused to move in 80 a manner different from the other members, and means for actuating the elements corresponding to the members so selected in the periods of rest of the step by step movement of the piece of mesh to cause these particular elements to act upon links of the piece of mesh in the row to which they correspond. 85

3. The combination of a support for a piece of link mesh fabric having the links thereof arranged in rows lengthwise and crosswise of the piece, means for moving the piece of fabric in the direction of its length, a power driven reciprocating carriage, a multiplicity of elements mounted on the carriage, each of these elements corresponding to a link in a crosswise row of links of the piece of mesh and adapted to act upon individual links to facilitate their removal from the piece of mesh, a pattern sheet, means for moving the pattern sheet in 100 correspondence with the movement of the piece of mesh, a plurality of members each corresponding to one of said elements and cooperating with the pattern sheet, means for moving the pattern sheet and said members relatively whereby certain of said members are selected and caused to move in a manner different from the other members, and means for moving the carriage relative to the mesh whereby the particular elements corresponding to the members selected by the pattern sheet are caused to act upon links of the piece of mesh in the row to which they correspond. 105

4. The combination of a support for a piece of link mesh fabric having the links thereof arranged in rows lengthwise and crosswise of the fabric, a multiplicity of elements each corresponding to a link in a crosswise row of links in the piece of mesh 110

and adapted to act upon individual links to facilitate their removal from the piece of mesh, means for moving the piece of mesh, and the elements relatively in the direction of the length of the piece of mesh, means for moving the piece of mesh and the elements relatively to cause the elements to contact with the piece of mesh, a pattern sheet, a plurality of members each corresponding to one of said elements and cooperating with the pattern sheet, means for moving the pattern sheet and the members relatively in the direction of length of the pattern sheet in correspondence with the relative movement of the elements and the piece of mesh in the direction of length of the piece of mesh, and means for moving the pattern sheet and said members relatively whereby certain of said members are selected and caused to move in a manner different from the other members, the members so selected by the pattern sheet thereupon serving to cause the elements corresponding thereto to act upon links of the piece of mesh in the row to which they correspond.

5. The combination of a support for a piece of mesh fabric containing a series of transverse rows of links, a multiplicity of elements, corresponding in number and position to the links in a row, for acting on the links to facilitate their removal from the fabric, a pattern sheet, a multiplicity of members cooperating with the pattern sheet and controlling the action of the elements, power driven means for giving the fabric and the elements a step by step relative movement, each step corresponding to a row of links across the fabric, and a second relative movement to cause the elements to engage the links, and for giving the pattern sheet and the members a step by step relative movement in correspondence with the step by step relative movement of the fabric and the elements, and power driven means for giving the members and the pattern sheet a second relative movement to cause selected members to be rendered operative.

6. The combination of a support for a piece of mesh fabric containing a series of transverse rows of links, a multiplicity of elements, corresponding in number and position to the links in a row across the fabric, for acting on the links to facilitate their removal from the fabric, a pattern sheet, a multiplicity of elements cooperating with and controlled by the pattern sheet, and in turn controlling the action of the elements, power driven means for giving the fabric and the elements a step by step relative movement, each step in the movement serving to present a new row of links to the elements, and a second relative movement occurring in the periods of rest of the step by step movement to cause the elements to engage the links, and also for giving the pattern sheet

and the members a step by step relative movement in correspondence with the step by step relative movement of the fabric and the elements, and power driven means for giving the members and the pattern sheet a relative movement occurring in the periods of rest of their step by step relative movement to cause selected members to be rendered operative.

7. The combination of a support for a piece of mesh fabric containing a series of transverse rows of links, a multiplicity of elements corresponding in number and position to the links in a row for acting on these links to facilitate their removal from the fabric, a pattern sheet, a multiplicity of elements cooperating with the pattern sheet and controlling the action of the elements, power driven means for giving the fabric and the elements a step by step relative movement, each step serving to present a new row of links to the elements, and a second relative movement in a plane substantially at right angles to the plane in which the first relative movement occurs, to cause the elements to engage the links, and for giving the pattern sheet and the members a step by step relative movement corresponding to the step by step movement first named, and power driven means for giving the members and the pattern sheet a relative movement in a plane at substantially right angles to the plane in which their first relative movement occurs to cause selected members to be rendered operative in accordance with the pattern.

8. The combination of a support for a piece of mesh fabric containing a series of transverse rows of links, a multiplicity of elements corresponding in number and position to the links in a row across the fabric for acting on individual links to facilitate their removal, a pattern sheet, a multiplicity of members cooperating with the pattern sheet and controlling the action of the elements, power driven means for giving the fabric and the elements a step by step relative movement, each step serving to present a new row of links to the elements, and a second relative movement occurring in the periods of rest of the step by step movement and in a plane substantially at right angles to the plane in which the step by step movement occurs to cause the elements to engage the links, and for giving the pattern sheet and the members a step by step relative movement in correspondence with the step by step movement first named, and power driven means for giving the members and the pattern sheet a relative movement to cause selected members to be rendered operative, this movement occurring in a plane substantially at right angles to the plane in which the step by step relative movement of the members and the sheet

takes place, and also occurring in the periods of rest of said step by step movement.

9. The combination of a support for a piece of mesh fabric containing a series of 5 transverse rows of links, power driven means for advancing the fabric with a step by step movement, each step corresponding in amount to the diameter of a link, a pattern sheet, power driven means for advancing 10 the pattern sheet with a step by step movement corresponding to the movement of the fabric, a multiplicity of elements corresponding in number and position to the links in a row across the fabric for acting 15 on individual links to facilitate their removal from the fabric, a multiplicity of members, one for each of said elements, cooperating with the pattern sheet and controlling the action of the elements, a carriage 20 on which the members and the elements are mounted, means for producing a relative movement of the carriage and the fabric to cause the elements to engage the links, and power driven means for producing 25 a relative movement of the members and the pattern sheet to cause selected members to render their associated elements operative.
10. The combination of a support for a piece of mesh fabric containing a series of 30 transverse rows of links, power driven means for advancing the fabric with a step by step movement, one row at a step, a multiplicity of elements corresponding in 35 number and position to the links in a row, for acting on individual links to facilitate their removal from the fabric, a multiplicity of members, one for each of the elements, for rendering the latter operative to act 40 upon the links, a pattern sheet, means for advancing the pattern sheet with a step by step movement in correspondence with the advance of the fabric, a reciprocating carriage on which the elements and the members 45 are mounted, power driven means for reciprocating the carriage toward and away from the fabric to bring the elements into contact with the links thereof, and power driven means for producing a relative movement 50 of the members and the pattern sheet to cause the sheet to render selected members operative whereby their associated elements are caused to act upon the links.

11. The combination of a support for a piece of mesh fabric containing a series of 55 transverse rows of links, means for advancing the fabric with a step by step movement, one row at each step, a pattern sheet, means for advancing the pattern sheet 60 with a step by step movement corresponding to the movement of the fabric, a multiplicity of elements corresponding in number and position to the links in a row, for operating upon individual links to facilitate 65 their removal from the fabric, and means controlled by the pattern sheet and movable into contact with the latter in the periods of rest of the step by step movement of the pattern sheet, the said means being rendered effective by its contact with 70 the sheet to cause selected elements to act upon the links corresponding thereto.
12. The combination of a support for a piece of mesh fabric containing a series of 75 transverse rows of links, means for advancing the fabric with a step by step movement, one row at each step, a pattern sheet, means for advancing the pattern sheet with a step by step movement corresponding to the movement of the fabric, a multiplicity of elements corresponding in number and position to the links in a row for acting on individual links to facilitate their removal from the fabric, 80 power driven means for advancing the elements toward the fabric to cause the elements to contact with the links thereof in the periods of rest of the step by step movement of the fabric, and a multiplicity of members, one for each of the elements, 85 controlled by the pattern sheet and movable into contact therewith in the periods of rest of the step by step movement of the sheet, these members in turn controlling the action of the elements upon the 90 links.

13. The combination of a support for a piece of mesh fabric containing a series of 95 transverse rows of links, means for advancing the fabric with a step by step movement, one row at each step, a pattern sheet, means for advancing the pattern sheet with a step by step movement corresponding to the movement of the fabric, a multiplicity of elements corresponding in number and position to the links in a row for acting on individual links to facilitate their removal from the fabric, a multiplicity of members, one for each of the elements, for controlling the action of the latter, 100 power driven means for moving the elements toward and away from the fabric, and power driven means for moving the members into contact with the sheet whereby selected members will render their associated elements effective to act upon the 105 links corresponding thereto.

14. The combination of a support for a piece of mesh fabric containing a series of 110 transverse rows of links, means for advancing the fabric with a step by step movement, one row at each step, a pattern sheet, means for advancing the pattern sheet with a step by step movement corresponding to the movement of the fabric, 115 a power driven reciprocating carriage, a multiplicity of elements corresponding in number and position to the links in a row operable to act upon individual links to facilitate their removal from the fabric and 120

movable as the carriage reciprocates into contact with these links, a multiplicity of members mounted on the carriage and operable to cause the elements to act upon 5 individual links to facilitate their removal from the fabric, and means for bringing the members into contact with the pattern sheet whereby selected members are rendered effective to cause their associated elements to act upon the links.

15. The combination of a support for a piece of mesh fabric containing a series of transverse rows of links, means for advancing the fabric step by step, one row 15 at a step, a power driven reciprocating carriage, a pattern sheet supported on the carriage and movable with a step by step movement corresponding to that of the fabric, a multiplicity of elements on the carriage 20 corresponding in number and position to the links in a row, and operable to act upon these links to facilitate their removal from the fabric, these elements being brought into contact with the links as the carriage reciprocates, a multiplicity of members, one for each element, movable into contact with the pattern sheet, and by their position of contact operable to render selected elements effective to act upon the links, and power 25 driven means for bringing the members into contact with the pattern sheet during the periods of rest of the step by step movement of the latter.

16. The combination of a support for a 35 piece of mesh fabric containing a series of transverse rows of links, means for advancing the fabric step by step one row at a step, a reciprocating carriage movable toward and away from the fabric, a pattern sheet supported on the carriage and 40 movable with a step by step movement corresponding to that of the fabric as the carriage reciprocates, a multiplicity of elements mounted on the carriage and corresponding in number and position to the 45 links in a row, these elements being brought into contact with the links of the fabric by the carriage during the periods of rest in the step by step movement of the fabric, 50 and a multiplicity of members under the control of the pattern sheet and in turn rendering selected elements effective to act upon the links in accordance with the pattern formed on the pattern sheet.

55. 17. The combination of a support for a piece of mesh fabric containing a series of transverse rows of links, a power driven reciprocating carriage, means operated by the reciprocation of the carriage for advancing the fabric with a step by step movement, one row of links at a step, a pattern sheet supported on the carriage, means operated by the reciprocation of the carriage for advancing the pattern sheet with a step 60 by step movement corresponding to the

movement of the fabric, a multiplicity of elements supported on the carriage and corresponding in number and position to the links in a row, these elements being operable to act upon individual links to facilitate their removal from the fabric, and being brought into contact with the links as the carriage reciprocates, and a multiplicity of members, one for each of the elements, controlled by the pattern sheet and in turn operable to render selected elements effective to act upon the corresponding links.

18. The combination of a support for a piece of mesh fabric containing a series of transverse rows of links, a power driven reciprocating carriage, means operated by the reciprocation of the carriage for advancing the fabric with a step by step movement, one row of links at a step, a pattern sheet supported on the carriage, means operated by the reciprocation of the carriage for advancing the pattern sheet with a step by step movement corresponding to the movement of the fabric, a multiplicity of elements supported on the carriage and corresponding in number and position to the links in a row, these elements being operable to act upon individual links to facilitate their removal from the fabric, and being brought into contact with the links as the carriage reciprocates, a multiplicity of members, one for each of the elements, mounted on the carriage and operable under the control of the pattern sheet to render the elements effective to act upon the links, and power driven means for bringing the members under the control of the pattern sheet whereby selected members are rendered operative.

19. The combination of a support for a piece of mesh fabric containing a series of transverse rows of links, a power driven reciprocating carriage, means operated by the reciprocation of the carriage for advancing the fabric with a step by step movement, one row at a step, a pattern sheet supported on the carriage, means operated by the reciprocation of the carriage for advancing the pattern with a step by step movement corresponding to that of the fabric, a multiplicity of selector bars corresponding in number and position to the links in a row for acting upon individual links to facilitate their removal from the fabric, and moved by the carriage into contact with the links, a multiplicity of feed dogs, one for each selector bar, each feed dog being rockable to a position controlled by the pattern sheet wherein it renders its associated selector bar effective to act upon a link, and power driven means for bringing all the feed dogs into contact with the pattern sheet whereby selected feed dogs will be rendered operative.

20. The combination of a support for a

piece of mesh fabric containing a series of transverse rows of links, a power driven reciprocating carriage moving toward and away from the fabric carried by the support, means operable by the reciprocation of the carriage for advancing the fabric with a step by step movement, one row of links at a step, a pattern sheet supported on the carriage, means operable by the reciprocation of the carriage for moving the pattern sheet with a step by step movement in correspondence with the movement of the fabric, a multiplicity of selector bars slidably mounted in the carriage and movable by the latter into contact with the fabric, these selector bars corresponding in number and position to the links in a row, and means operable in the periods of rest of the pattern sheet and under the control of the latter for causing selected bars to act upon individual links to facilitate their removal from the fabric.

21. The combination of a support for a piece of mesh fabric containing a series of transverse rows of links, a power driven reciprocating carriage moving toward and away from the fabric carried by the support, means operable by the reciprocation of the carriage for advancing the fabric with a step by step movement, one row of links at a step, a pattern sheet supported on the carriage, means operable by the reciprocation of the carriage for moving the pattern sheet with a step by step movement in correspondence with the movement of the fabric, a multiplicity of selector bars loosely mounted in the carriage and movable by the latter into contact with the fabric, these selector bars corresponding in number and position to the links in a row, a multiplicity of feed dogs, one for each selector bar, operable under the control of the pattern sheet for rendering selected bars effective to act upon corresponding links to facilitate their removal from the fabric, and power driven means operable for bringing the feed dogs into contact with the pattern sheet, during the periods of rest of the step by step movement of the latter, whereby selected dogs are rendered effective.

22. The combination of a support for a piece of mesh fabric containing a series of transverse rows of links, means for moving the mesh in the direction of its length with a step by step movement, one row at a step, a multiplicity of elements corresponding in number and position to the links in a row and operable to act on individual links to facilitate their removal from the fabric, means for giving the elements and the mesh a relative movement occurring in the periods of rest of the step by step advance of the fabric to cause the elements to act upon the links, a pattern sheet, means for advancing the pattern sheet with a step by step move-

ment in correspondence with the step by step movement of the fabric, a multiplicity of members, one for each of the elements, operable to render the said elements effective to act upon the links, these members having a portion adapted to contact with the elements and another portion adapted to contact with the pattern sheet, and means for producing a relative movement of the pattern sheet and the members occurring in the periods of rest of the step by step movement of the pattern sheet to cause the pattern-engaging portion of said members to contact with the pattern, whereby selected members are rendered effective.

23. The combination of a support for a piece of mesh containing a series of transverse rows of links, means for advancing the mesh in the direction of its length with a step by step movement, a power driven carriage reciprocating toward and away from the face of the mesh, a multiplicity of selector bars supported in the carriage and corresponding in number and position to the links in a row across the mesh, these selector bars being brought into contact with the mesh as the carriage reciprocates, a pattern sheet, means for advancing the pattern sheet with a step by step movement corresponding to the step by step movement of the fabric, and a multiplicity of feed dogs, one for each selector bar, brought under the control of the pattern sheet during the periods of rest of the movement of the latter, the pattern sheet thus rendering selected feed dogs effective to cause their associated selector bars to act upon the individual links of the fabric to facilitate their removal therefrom.

24. The combination of a support for a piece of mesh fabric containing a series of transverse rows of links, means for moving the fabric in the direction of its length with a step by step movement, one row at a step, a power driven reciprocating carriage movable toward and away from the face of the fabric, a multiplicity of selector bars slidably mounted in the carriage and lying substantially normal to the face of the mesh, each selector bar being operable to act upon an individual link to facilitate its removal from the fabric, a pattern sheet supported on the carriage, means operable by the movement of the carriage for advancing the pattern sheet with a step by step movement corresponding to the step by step advance of the mesh, a multiplicity of feed dogs, one for each selector bar, movable to a position in which each feed dog is controlled by the pattern sheet, selected feed dogs by their contact with the sheet being rendered effective to cause the corresponding selector bars to act upon the links to facilitate their removal from the mesh, and means operable during the periods of rest of the

step by step advance of the pattern sheet for bringing all of the feed dogs into contact with the latter whereby selected dogs are rendered effective.

25. The combination of a rotary support for a piece of mesh fabric containing a series of transverse rows of links, a portion of the fabric depending from this support, a multiplicity of elements corresponding in 10 number and position to the links in a row across the mesh, means operable to cause the elements to contact with the depending portion of the mesh during the periods of rest of the latter, and control means for 15 causing selected elements to act upon individual links to facilitate their removal from the fabric.

26. The combination of a rotary support for a piece of mesh fabric containing a 20 series of transverse rows of links, a portion of the fabric depending from this support, a multiplicity of elements corresponding in number and position to the links in a row across the mesh, means for giving the 25 support a step by step rotation to cause the mesh to be advanced one row at a step, means for moving the elements against the depending portion of the fabric, and control means for rendering selected elements 30 operative to act upon individual links to facilitate their removal from the fabric.

27. The combination of a rotary support for a piece of mesh fabric containing a 35 series of transverse rows of links, a portion of the fabric depending from this support, a multiplicity of elements corresponding in number and position to the links in a row across the mesh and operable to act upon individual links to facilitate their removal 40 from the fabric, means for giving the support a step by step rotation to cause the mesh to be advanced one row at a step, means for moving the elements against the depending portion of the fabric, a pattern 45 sheet movable with a step by step movement corresponding to the movement of the fabric, and a plurality of members, one for each of the elements, interposed between the pattern sheet and the elements and operable in the periods of rest of the step by step movement of the pattern sheet to govern 50 the action of the elements in accordance with the pattern carried by the sheet.

28. The combination of a rotary support 55 for a piece of mesh fabric containing a series of transverse rows of links, a ratchet wheel carried on the support, a power driven reciprocating carriage, a pawl engaging the ratchet wheel and operable by the reciprocation of the carriage for advancing the fabric one row per reciprocation, a multiplicity of selector bars corresponding in 60 number and position to the links in a row across the mesh, these selector bars being

mounted in the carriage and movable by the latter to contact with individual links of the mesh, a pattern sheet, a rotary support for the pattern sheet mounted on the carriage and provided with a ratchet wheel, a pawl on the carriage engaging this ratchet wheel and operable by the reciprocation of the carriage to advance the pattern sheet with a step by step movement corresponding to that of the fabric, a multiplicity of feed dogs pivotally supported on the carriage, one for each of the selector bars, and means for moving the group of feed dogs simultaneously into engagement with the pattern sheet whereby selected dogs are rendered effective to lock their associated selector bars in operative position in the carriage.

29. The combination of a support for a piece of mesh fabric containing a series of transverse rows of links, a power driven reciprocating carriage, means operable by the reciprocation of the latter for advancing the fabric with a step by step movement, one row at a step, a multiplicity of elements corresponding in number and position to the links in a row across the fabric, these elements being loosely mounted in the carriage and moved into contact with the fabric by the reciprocation of the carriage, a pattern sheet supported on the carriage, means operable by the movement of the latter for advancing the pattern sheet with a step by step movement corresponding to that of the fabric, a multiplicity of locking members supported on the carriage, one for each element, and means for moving the locking members into engagement with the pattern sheet whereby selected members, determined by the pattern sheet, render their associated elements effective to act upon the links to facilitate their removal from the fabric.

30. The combination of a support for a piece of mesh fabric containing a series of transverse rows of links, a power driven reciprocating carriage movable toward and away from the fabric, a multiplicity of selector bars corresponding in number and position to the links in a row across the mesh, mounted in the carriage and movable by the latter into contact with the fabric, a pattern sheet supported on the carriage and movable by the reciprocation of the latter with a step by step movement corresponding to that of the fabric, a multiplicity of locking members, one for each selector bar, disposed between the pattern sheet and the selector bars and a member rotating in timed relation to the movement of the pattern sheet and operable in the periods of rest of the step by step movement of the latter to bring all of the locking members into contact with the pattern

sheet, whereby selected locking members render their associated selector bars effective to act upon individual links to facilitate their removal from the fabric.

5 31. In a machine for treating mesh fabric containing a series of transverse rows of links to facilitate the removal of links therefrom in accordance with a predetermined pattern, the combination of a support 10 for a piece of fabric from which a free end of the fabric depends, a multiplicity of elements corresponding in number and position to the links in a row and operable to act upon individual links in a row in the 15 depending portion to facilitate their removal from the fabric, and power driven means for giving the fabric and the elements a step by step relative movement, whereby the rows of links are successively 20 presented to the elements, and for giving the fabric and the elements a relative movement occurring in the periods of rest of the movement first named to cause the elements to act upon individual links.

25 32. In a machine for treating mesh fabric containing a series of transverse rows of links to facilitate the removal of links therefrom in accordance with a predetermined pattern, the combination of a support for a 30 piece of fabric from which a free end of the fabric depends, a multiplicity of elements corresponding in number and position to the links in a row across the mesh and operable to act upon individual links in a row in the 35 depending portion to facilitate their removal from the fabric, power driven means for giving the fabric and the elements a step by step relative movement whereby the rows of links are successively presented to the elements, and for giving the fabric and the 40 elements a relative movement occurring in the periods of rest of the movement first named to cause the elements to act upon individual links, and means for controlling the 45 action of individual elements whereby selected links may be acted upon in accordance with a predetermined pattern.

33. In a machine of the class described, a support for a piece of mesh fabric containing a series of transverse rows of links, a free end of the fabric depending from the support, means for advancing the piece of mesh in the direction of its length with a step by step movement a row at a step, and 50 power driven means movable into contact with the depending end of the fabric during the periods of rest of said step by step movement, and operable to act on individual links in a row to facilitate their removal from the 55 fabric.

34. In a machine of the class described, a support for a piece of mesh fabric containing a series of transverse rows of links, a free end of the fabric depending from the

support, means for advancing the piece of 65 mesh in the direction of its length with a step by step movement a row at a step, and a multiplicity of elements, corresponding in number and position to the links in a row, these elements being movable into contact 70 with the free end of the fabric in the periods of rest of the step by step movement thereof, and operable to act upon individual links to facilitate their removal from the fabric. 75

35. In a machine of the class described, the combination of a support for a piece of mesh fabric containing a series of transverse rows of links, a free end of the fabric depending from the support, power driven 80 means for advancing the mesh in the direction of its length with a step by step movement, one row at a step, means operable in the periods of rest of said step by step movement to act upon individual links in the 85 depending portion of the fabric to facilitate their removal therefrom, and control means for controlling the action of the means last mentioned whereby the links may be acted on in accordance with a predetermined pattern. 90

36. In a machine of the class described, the combination of a support for a piece of mesh fabric containing a series of transverse rows of links, power driven means for advancing the mesh in the direction of its length with a step by step movement, one row at a step, a multiplicity of elements corresponding in number and position to the links in a row and operable in the periods 95 of rest of the step by step movement of the mesh to act upon individual links to facilitate their removal from the fabric, a pattern sheet movable with a step by step movement corresponding to the movement of the mesh, 100 and a multiplicity of members, one for each of the elements, interposed between the elements and the pattern sheet and movable into contact with the latter, these members serving to render selected elements operative 105 under the control of the pattern sheet. 110

37. In a machine of the class described, the combination of a support for a piece of mesh fabric containing a series of transverse rows of links, a free end of this fabric depending from the support, power driven means for advancing the fabric with a step by step movement, one row at a step, means for acting upon individual links in a row located in the free end of the fabric to facilitate their removal from the fabric, and power driven means for causing the means last mentioned to engage the fabric during the periods of rest in the step by step movement of the latter. 115 120

38. In a machine of the class described, the combination of a support for a piece of mesh fabric containing a series of trans-

verse rows of links, a free end of this fabric depending from the support, power driven means for advancing the fabric with a step by step movement, one row at a step, means 5 for acting upon individual links in a row located in the free end of the fabric to facilitate their removal from the fabric, power driven means for causing the means last mentioned to engage the fabric during the 10 periods of rest in the step by step movement of the latter, and means for controlling the action of said mesh-engaging means to cause the links to be acted upon in accordance with a predetermined pattern.

39. In a machine of the class described, the combination of a support for a piece of mesh fabric containing a series of transverse rows of links, a free end of the fabric depending from this support, a pattern sheet, means for advancing the fabric in the direction of its length with a step by step movement, a row at a step, and for advancing the pattern sheet with a corresponding step by step movement, and means 20 interposed between the pattern sheet and the depending portions of the fabric and operable during the periods of rest of the movement of the piece of fabric and the pattern sheet and under the control of the pattern sheet for acting upon selected links in successive rows in the depending portion of the fabric to facilitate their removal therefrom.

40. In a machine for acting upon the links of a link mesh fabric containing a series of transverse rows of links to facilitate the removal of individual links therefrom, the combination of a multiplicity of selector bars, one for each link in a row 35 across the fabric, a pattern sheet for controlling the action of the selector bars, a multiplicity of feed dogs, one for each selector bar, and power driven means for bringing the feed dogs and the pattern sheet into contact whereby selected feed dogs 40 lock their associated selector bars in operative position.

41. The combination of a support for a piece of mesh containing a series of transverse rows of links, a power driven reciprocating carriage, means for advancing the fabric in the direction of its length with a step by step movement, one row at a step, a multiplicity of selector bars, one for each 50 link in a row, and operable to act upon individual links to facilitate their removal from the fabric, a pattern sheet, means for advancing the pattern sheet with a step by step movement corresponding to the step by step movement of the fabric, a multiplicity of feed dogs, one for each selector bar, these feed dogs being mounted on a common support and movable to positions in which they render their associated 55 selector bars operative, this action of the

feed dogs being under the control of the pattern sheet, and a rotary member acting on all of the feed dogs and causing them to contact with the pattern sheet in the periods of rest of the step by step movement of the latter whereby feed dogs, selected by the pattern sheet, act upon their associated selector bars.

42. The combination of a support for a piece of link mesh fabric containing a series of transverse rows of links, a power driven reciprocating carriage, means operable in accordance with the reciprocation of the carriage for advancing the piece of mesh with a step by step movement in the direction of its length, one row at a step, a multiplicity of selector bars corresponding in number and position to the links in a row mounted in the carriage and movable with the latter into contact with the links, a pattern sheet, means operable in accordance with the reciprocation of the carriage for advancing the pattern sheet with a step by step movement corresponding to that of the piece of fabric, a multiplicity of feed 70 dogs, one for each selector bar, interposed between the pattern sheet and the bars, and operable under the control of the pattern sheet for rendering selected selector bars effective to act upon corresponding individual links 75 to facilitate their removal from the fabric, and a rotary member moving in timed relation with the movement of the pattern sheet 80 and operable in the periods of rest of the latter to cause all the feed dogs to contact with the sheet whereby selected dogs are rendered effective.

43. The combination of a support for a piece of mesh fabric containing a series of transverse rows of links, a free end of this fabric depending from the support, a power driven reciprocating carriage, means operable in accordance with the reciprocation of the carriage for advancing the mesh with a step by step movement in the direction of its length, one row at a step, a multiplicity of selector bars corresponding in number 105 and position to the links in a row mounted in the carriage and movable into contact with individual links in a row in the depending portion of the fabric by the reciprocation of the carriage, a pattern sheet, means operable in accordance with the reciprocation of the carriage for advancing the pattern sheet with a step by step movement corresponding to the movement of the fabric, a multiplicity of feed dogs, one for each selector bar, interposed between the pattern sheet and the selector bars and operable under the control 110 of the pattern sheet to render their associated selector bars effective to act upon the links to facilitate their removal from the fabric, and a member rotating in timed relation with the step by step movement of the pattern sheet and operable in the periods of 115 120 125 130

rest of the movement of the latter to bring the feed dogs into contact with the sheet whereby selected dogs are brought into action.

5. 44. In a machine of the character described, a support for a piece of link mesh fabric, a device for spreading open links of the fabric to render them removable from adjacent links, and means for moving the support and the device relative to each other to cause the latter to act on the links of the fabric along the outline of the pattern of an article, thereby to render the article removable from the fabric.
- 10 45. In a machine of the character described, a support for a piece of link mesh fabric, a selector bar adapted to render links of the fabric removable from adjacent links by entering the links and spreading them open, and means for moving the support and the selector bar relative to each other to cause the latter to engage links of the fabric along the outline of the pattern of an article, thereby to render the article removable from the fabric.
- 15 46. In a machine of the character described, a support for a piece of link mesh fabric, means for actuating the support to move the fabric step by step, a series of slidably mounted selector bars adapted to render links of the fabric removable from adjacent links by entering the links and spreading them open, a pattern, means coacting with the pattern for selectively fixing the selector bars in operative positions, and means for bringing the selector bars and fabric into contact to cause the bars fixed in operative positions to act upon corresponding links of the fabric along the outline of the pattern of an article, thereby to render the article removable from the fabric.
- 20 47. In a machine of the character described, a support for a piece of link mesh fabric, means for actuating the support to

move the fabric step by step, a carriage, 45 selector bars slidably mounted on said carriage adapted to render links of the fabric removable from adjacent links by entering the links and spreading them out, a pattern consisting of a perforated roll, said perforations outlining the design of the article to be cut from the fabric, feed dogs coacting with said perforations for selectively fixing said bars in operative positions, and means for moving said feed dogs, carriage and pattern in timed relation with the movement of the fabric to cause the bars fixed in position to act on the links of the fabric along the outline of the pattern of an article, thereby to render the article removable from the 60 fabric by the removal of said links.

48. In a machine for treating link mesh fabric to facilitate the removal of pieces therefrom, the combination of a support for a piece of fabric, and means for spreading a link of the fabric to facilitate its removal.

49. In a machine for treating link mesh fabric to facilitate the removal of pieces therefrom, the combination of a support 70 for a piece of link mesh fabric, a plurality of spreading devices adapted to enter rings of the fabric to spread them and thus facilitate their removal, and means for selecting the spreaders to be operated to spread links 75 of the fabric in accordance with a predetermined design.

50. In a machine for treating link mesh fabric to facilitate the removal of pieces therefrom, the combination of a support for 80 the fabric and automatic means for spreading links of the fabric to permit removal thereof in accordance with a predetermined design.

In testimony whereof we affix our signatures.

OSCAR SODERSTROM.
FRED HARRIS LYNDS.
